UNITED STATES PATENT OFFICE.

ARTHUR J. BAZELEY AND WILLIAM J. METZGER, OF CLEVELAND, OHIO, ASSIGNEES,
BY MESNE ASSIGNMENTS, TO NATIONAL MALLEABLE AND STEEL CASTINGS COMPANY, OF CLEVELAND, OHIO, A CORPORATION OF OHIO.

CHAIN LINK.

Application filed November 4, 1921. Serial No. 512,756.

Fig. 1 is a plan, partly in section, of one form of our improved chain link; Fig. 2 is an elevation thereof; Fig. 3 is an elevation similar to Fig. 2 but with the detachable 5 member of the link in the position in which it is applied to the link; Figs. 4 and 5 show the main portion of the link in elevation and plan, respectively; Figs. 6 and 7 show the detachable portion of the link in plan and 10 elevation, respectively; Fig. 8 is a plan of a modified form of our invention; Fig. 9 is an elevation thereof; Fig. 10 is a section on lines X—X of Fig. 8; Fig. 11 is a plan, partly in section, of a further modification 15 of our invention; Fig. 12 is an elevation thereof; Figs. 13 and 14 are sections on lines XIII—XIII and XIV—XIV, respectively, of Fig. 11; and Fig. 15 is a side elevation of the detachable member.

Our invention relates to links for anchor 20 cables and comprises a separable link or shackle which may be employed to repair a broken anchor chain, replace a defective link, or to connect together the "shots" of chain 25 which make up a length of cable. Our invention also comprises the various features which we shall hereinafter described and claim.

Referring to the drawings, A indicates the 30 main body of the link, B the T-shaped separable member, and C a rivet, pin or bolt for securing the member B in the link body A. The link A has a seat or depression 2 on the transverse axis of the link, and opposite 35 this depression 2 is an opening 3 clear through the other side of the link, and the ends of the link terminate in similarly formed arms 4 in each of which is a groove 5 formed by arcs struck from the transverse 40 axis of the link A as a center. The grooves 5 have under-cut sides 6 and 7 which form lugs 8 and 9 toward the outer side of the link.

The T-shaped member B has at the bottom 45 of its leg 10 a projection 11 which fits into the recess 2. The leg 10 forms the stud of the link, and the arms 12 of the T fill in the open side of the link. The leg 10 has arc-shaped shoulders 13 extending in the direction 50 of the horizontal axis of the link, which form bearings against the interior side faces of the link A and serve to hold the piece B in position and also to stiffen the link A. The member B has on the inner faces of its

arms 12 circular projections 14 struck on 55 radii from the axis of the member B, which corresponds to the transverse axis of the link. The projections 14 have lateral extensions 15 and 16 to engage the under-cut portions 6 and 7 of the grooves 5.

Where it is desired to connect two links in the ends of lengths of chain the link A is threaded through the free eyes of such links, the three links are pulled out straight and the T-member B is inserted through the 60 open side 3 of the link with its long dimension at right angles to the body of the link, as is shown in Fig. 3. The projection 11 is seated in the recess 2 and the piece B is then rotated through 90° about its axis, thus 65 causing the shoulders 13 to engage the inner side faces of the link and the projections 14 to enter into the grooves 5 on the arms 4 of the link. In this position the lateral extensions 15 and 16 of the projections 14 70 will engage and form an interlock with the under-cut sides 6 and 7 of the grooves 5. Rotation of the member B after it is in the 75 position shown in Figs. 1 and 2 is prevented by the rivet or pin C, which may be inserted into the counter-sunk aperture 17 and when inserted has a bearing against the end of an arm 4.

When the member B is in the position just 80 described the interlocking of the parts prevents them from spreading or pulling apart. Thus the projections 14 with their extensions 15 and 16 hold the arms 4 from spreading, while the shoulders 13 hold the member B firmly against movement along the transverse axis of the link and also support the 85 link A against collapse.

In Figs. 8, 9 and 10 we have shown a modified form of our invention in which the T-member B is applied from the side of the 90 link. In this form the lower end of the leg of the T is in the form of a hook 21 which engages the inner face of a lug 22 comprising part of the projection 23 which forms a base for the stud. The T-shaped member B is applied in a direction perpendicular to a plane lying in the horizontal axis of the link, so that the projections 24 on the arms of the member B are brought into engagement with the hooks 25, and the 95 hook 21 engages the lug 22.

When the member B is in position it is held against outward movement by the hook

21, which engages lug 22 and by the re-entrant angles of hooks 24 and 25, which also prevent spreading of the arms of the link A. Sidewise movement is prevented by 5 the rivet or pin C, which is inserted through the registering apertures 26 and 27 in the leg of the member B and in the projection 23.

In Figs. 11 to 15, inclusive, the T-member 10 is inserted along the transverse axis of the link A. The ends of the arms of the link A have a U-shaped recess 31 and terminate in a flange 32 beyond the recess. The arms of 15 the T-member B terminate in a U-shaped projection 33 which fits into the U-shaped recess 31 and engages the flange 32. The leg of the T is circular in cross section and the lower end seats in a depression 34 in the link A, in which it is held by a taper pin C which seats in registering apertures in the 20 link A and in the lower end of the leg. One end of the aperture 36 in the link A is counter sunk for the reception of a soft metal collar or washer 37, which is pressed in this counter-sunk portion, filling it and a groove 25 38 in the pin C. Mounted on the leg of the T-shaped member B is a spacing member 39 which holds the parts of the link against collapse and also tends to hold the parts rigidly together.

30 We have found that links constructed in accordance with our invention may be manufactured commercially because of their simple construction at low cost and when used have been found to be comparable in strength 35 and durability with links cast in one piece.

The terms and expressions which we have employed are used as terms of description and not of limitation, and we have no intention, in the use of such terms and expressions 40 of excluding any mechanical equivalents of the features shown and described, or portions thereof, but recognize that various structural modifications are possible within the scope of the invention claimed.

45 What we claim is:

1. A chain link comprising a member hav-

ing an open side terminating in arms extending toward each other, a closure member engaging said arms, the engaging surfaces upon said members being curved about the 50 transverse axis of the link, all of the curved engaging surfaces of said members extending uninterruptedly from the upper to the lower surface.

2. A chain link comprising a C-shaped member having a closed side and an open side, the open side terminating in arms extending toward each other and forming part of the inner surfaces of the link, a one-piece T-shaped closure member for said open side, 55 said closure member having a projection and recess engagement with said arms near the ends thereof arranged to prevent the spreading of said arms, said closure member having a stem comprising the stud of the link, the said stem seating and being secured in a recess in the inner face of the closed side, and securing means engaging the said members and preventing relative movement thereof, the link when the said members are secured together forming a rigid link with identically shaped and symmetrical surfaces.

3. In stud links for anchor chains, a link having an open side terminating in arms extending toward each other, said arms having 75 arc-shaped grooves, a member mounted in the transverse axis of the link having projections arranged to interlock in said grooves on rotation of the said member, and means for securing the members against relative 80 movement.

4. In stud links for anchor chains, a link having an open side and a T-shaped member, the leg of the T-shaped member comprising the stud of the link and having a 85 bearing in a recess on the closed side of the link, the T-shaped member having projections interlocking with projections on the arms of the link and also carrying shoulders engaging inner side faces of the link.
